UNITED STATES PATENT OFFICE.

JOHN J. SHEA, JR., OF ELMHURST, NEW YORK.

COLLAPSIBLE STRUCTURE.

Application filed May 13, 1921. Serial No. 469,084.

To all whom it may concern:

Be it known that I, JOHN J. SHEA, Jr., a citizen of the United States, residing at Elmhurst, in the county of Queens and State of New York, have invented certain new and useful Improvements in Collapsible Structures, of which the following is a full, clear, and exact description, such as will enable others skilled in the art to which it appertains to make and use the same.

This invention relates to collapsible structures of wood or metal and the principles involved therein are susceptible of numerous and varied applications. It is especially useful in connection with shipping containers, portable buildings of various descriptions, car construction, furniture and the like.

It is an object of the invention to provide an improved structure of the class mentioned which may readily be collapsed into a unit of small volume as compared with its volume when expanded, and when so collapsed, forms a compact self-contained unit.

Another object is to provide a structure of the class mentioned which, when expanded, forms a rigid structure the elements whereof are firmly locked in cooperative relationship, and which is useful in divers applications.

Still another object is to provide an improved collapsible structure in which the parts are assembled in cooperative relationship in expanded form for various uses, or the parts may be disassembled and grouped into a small unit portable in character, with a minimum of time and effort, the operations of disassembling and assembling requiring no special skill.

Still another object is to provide an improved collapsible structure adapted for divers uses and utilizing readily detachable members assembled when detached into a single element of the structure and forming a compact unit of relatively small volume susceptible of easy transportation and convenient for storage.

Another object is to provide an improved self-locking structural joint for rigidly supporting one structure or member at an angle to another, and which is capable of easy assembly or disassembly.

Other objects will be in part obvious in connection with the following detailed description and in part pointed out in connection therewith.

In the accompanying drawing forming a part of this specification, in which are shown several illustrative embodiments of the invention;

Figure 1 is a perspective view of a construction embodying the invention the parts being partially disassembled for clearness of disclosure.

Fig. 2 is a fragmentary enlarged transverse sectional view taken approximately on the line 2—2 of Fig. 1, looking in the direction of the arrow, and showing the improved joint construction embodied in the invention.

Fig. 3 is a top plan view of the construction shown in Fig. 2.

Fig. 4 is a fragmentary enlarged sectional view taken approximately on the line 4—4 of Fig. 2.

Fig. 5 is a perspective view showing the disassembled complementary members of the joint between the upper end of a post and one end of a transverse brace.

Fig. 6 is a detail view of a locking mechanism for the slats of the structure.

Fig. 7 is an enlarged perspective view, similar to Fig. 5, but showing the complementary members of the joint at the opposite end of the brace from that shown in Fig. 5.

Fig. 8 is a transverse sectional view taken approximately at the line 8—8 of Fig. 1 showing the parts assembled.

Fig. 9 is a detailed fragmentary view showing the locking bar for the floor doors.

Fig. 10 is a fragmentary detailed view of a modification.

Fig. 11 is a sectional view corresponding to Fig. 2, but showing a modification of the joint for securing a post in position.

Fig. 12 is a sectional view on the line 12—12 of Fig. 11.

Fig. 13 is a fragmentary detailed enlarged view corresponding to Fig. 2 but showing a modified construction.

Fig. 14 is an elevation of the upper end of the post shown at the right in Fig. 13.

Referring to the drawing for a detailed description of the disclosed embodiments of the invention, and first to Figs. 1 to 9, a base section or unit is indicated at 1 and a superstructure is indicated generally at 2. The base section preferably includes longitudinal side sills 3; an intermediate longitudinal sill 4, transverse end sills 5, and an intermediate transverse sill 6. The base

105

110

is provided with a lower external floor or sheathing 7, and an upper floor principally comprised in doors 8 hinged to the side sills and closing on the upper surface of the central longitudinal sill 4. This construction provides compartments A between the upper and lower floors for storage of the elements of the superstructure to be later described.

The doors 8 are provided at the free edges 10 thereof with rabbets 9 for receiving longitudinal locking bars 10 having a stiffening rib 10' on its lower face. The bars 10 lie flat with the upper surface of the doors forming a smooth surface, which is 15 desirable in use in the many applications of the unit. Each locking bar 10 is preferably provided at one end with a tongue 11 adapted to engage in an opening in an end plate 12 secured to the end sill, and 20 at its opposite end with a slot 13 for receiving a staple 14 to which a suitable padlock or similar locking device may be applied. As will be seen, two similar locking bars are preferably employed in practice, connected by tongues 11 to opposite end plates 12, and meeting at the center of length of the base section, as will be clear from Fig. 1. The detachable knockdown superstructure 2 comprises upright posts 15 arranged in 25 spaced opposed relationship along the opposite side sills 3, to which they are attached by means of improved structural joints forming a part of this invention. The posts 15 are secured and braced in position 30 by means of transverse braces 16, the opposite ends of which are specially formed to cooperate with complementary post formations for providing rigid joints therebetween which are easily assembled or disassembled 35 and are self-locking in position. The adjacent transverse frames formed by a pair of posts with connecting braces, may be laterally braced by means of rods 17, shown as attached to the transverse braces in any 40 desirable manner, such as by securing plates 17'. One pair of posts, with connecting brace 16, is disposed adjacent each end of the base section, and one pair substantially intermediate thereof, but it is obvious that 45 as many pairs of posts as desired may be employed in the construction of any given unit. For completely closing the structure when expanded, suitable panels or slats 18 are supported by the posts 15, channel members 50 19 being provided for this purpose, for slidably receiving the ends of these panels. The channel members may take any desired form, but are preferably of metal and are secured to the faces of the 55 posts in inclined position so that the slats when supported therein overlap each other from above forming an effective watershed. Each slat, except the lowest, may be provided with one or more clips 20 which are 60 preferably Z shaped in section and have 65

their downwardly extended flanges disposed to receive the upper edge for the next adjacent lower panel or slat for holding these elements in relative positions and preventing the same from springing away from each other. Top slats 21 are held in channel sections 22, similar to the channel members 19, and are secured to the opposed faces of the adjacent cross braces 16. These channels 22 may be overlapped from above, supporting the slats in inclined overlapping relationship, so as to form watershedding surfaces as shown in Figs. 1 and 8. Securing clips 23, preferably of Z-section, similar to clips 20, may also be provided on slats 21 engaging the edges of adjacent slats for holding them in position.

The upper most side slat (Figs. 1 and 6) is provided with one or more locking devices shown as a locking bar 24, pivoted to the slat, the upper end thereof being adapted to engage slot 25 in the lowermost roof slat 21 for locking all the slats in position. It will be noted that the edge of the lower roof slat overlies the upper edge of the uppermost wall slat preventing upward movement of the latter. It will therefore be seen that the side wall and top wall slats are securely locked in position from removal from without, but may be released from within by operation of the locking levers 24.

The ends of the superstructure may be closed by swinging doors 26, hinged to the end posts. These doors are hung to swing outwardly and are preferably mounted by means of special detachable hinges 27 incapable of detachment from without, but readily detachable from within the structure. This hinge forms the subject-matter of a companion application, Serial No. 469,358 filed May 13, 1921, and further disclosure herein is considered unnecessary. The doors may of course be provided with suitable locking means.

Each post is detachably secured to the base section by special joint construction comprising, as shown in Figs. 2 and 4, a tenon 28 on the end of the post which may be co-extensive in thickness with the thickness of the post, and having a lateral inwardly extending projection or arm 29 with a terminal stop or toe 30. The outwardly disposed side of said tenon, or that opposed to toe 30, is curved approximately on the arc of a circle as shown at 31, the tenon being preferably thickened adjacent its attachment to the post for stiffening the same as shown in Fig. 2.

A complementary recess or mortise 32 is provided in a framing member of the base section for receiving the tenon 28 and has an overhanging wall 33 overlying the lateral extension of the tenon, and disposed in the angle between the latter and the

thickened portion thereof. The mortise is provided with a curved wall corresponding to the curved wall of the tenon, and is otherwise formed to cooperate with the 5 walls or faces of the tenon for supporting the latter securely in position. One or more drain apertures 34 may be provided leading downwardly from the mortise permitting the escape of dirt, moisture or other 10 foreign matter.

As shown at the right in Fig. 2 and in Fig. 7, the upper end of the post is provided with a recess or mortise 35, somewhat similar in formation to the mortise 15 32, and has a downwardly extending recess for receiving a laterally offset toe 36 of a tenon 37. The wall 38 is disposed to underlie the offset portion or toe 36 and cooperate with the same to prevent removal 20 of the brace 16 except by a transverse swinging movement of the latter. This tenon is preferably formed by cutting away portions of the brace 16 across the lower face thereof as indicated at 39, and cutting away a portion thereof above the tenon 25 forming a recess as indicated at 40, the lateral remaining portions providing walls 41 between which is received a complementary tenon 42 on the inner faces of the upper end of said post and spaced above 30 said mortise 35. These mutually engaging parts afford a joint specially rigid when assembled. It will be noted that the tenon 42 overlies tenon 37 when in assembled position, preventing disengagement of the 35 parts by upward movement of the brace, while movement thereof to the left is prevented by the engagement of the overhanging wall 38 with the toe 36. It will thus be seen that a self-locking joint is provided 40 incapable of disassembly except by swinging movement of the brace, as will be understood.

The joint between the opposite end of 45 brace 16 and the upper end of the opposite post 15 comprises complementary formations on brace and post engageable by lateral movement of one with respect to the other. For this purpose as shown in Figs. 2 and 5, the end portion of the cross brace is provided near its upper surface 50 with a recess or mortise 43 having a downwardly extended pocket 44 with wall 45 lying therebetween and the end of the brace. The post is provided with a projection or 55 tenon 46, extending from the inner face thereof and having a downwardly projecting lug 47 for engaging in pocket 44, the tenon 46 being adapted to be received in mortise 43. A locking device is provided 60 for holding the complementary parts of the joint in engagement, comprising a block 48, telescopically mounted in a pocket 49 in the face of the post and secured in position by a leaf-spring 50 secured to the

post and tensioned to hold the locking block 70 in extended position. It will be obvious that during upward movement, the end of the brace will engage spring 50 moving the block 48 inwardly, the latter being carried out again by the spring into engagement with the lower face of the brace when the parts have reached final engaging position as clearly shown in Fig. 2 of the drawing. In this position, the parts are positively held from removal in any direction by inter-engagement of the complementary parts of the joint, the lock block 48 supporting the brace in assembled position. It will be obvious that the parts may readily be disassembled by pressing the locking block 48 80 inwardly so as to release the end of the brace 16 to downward movement.

From the foregoing description, it will be perceived that a complete rigid structure can be assembled from its component parts. It can readily be disassembled and collected in the compartments A provided in the base section to form a compact unit of small volume and of portable character.

Assuming the elements of the superstructure to be stored in the compartments A, and it is desired to erect the superstructure for use, the lock is removed from the locking bar 10, and the latter taken out to permit the doors 8 to be opened and the stored elements of the superstructure to be removed. The doors may then be closed and the locking bar replaced forming a smooth floor surface for the compartment, or they may be left open and upwardly turned against the near faces of the posts leaving the storage compartments A available for storage purposes.

To attach the posts to the base section, the tenon formation 28 is inserted into its respective mortise, while the post inclines inwardly as indicated in dotted lines in Fig. 2. The post is then swung outwardly into vertical position, the tenon sliding into position in its mortise and the lateral extending arm 29 engaging beneath the overhanging wall 33. The toe 30 of the tenon engages against the end of the mortise preventing outward movement of the post beyond its vertical position. When two opposite posts are thus placed in position, the tenon 37 of the cross brace 16 is inserted into its mortise 40, while the brace inclines downwardly as shown in dotted lines in Fig. 2. The brace is then swung upwardly causing the toe 36 to move into position in the downwardly extending pocket of said mortise, the complementary tenon 42 on the post overlying tenon 37, locking the parts firmly in position as clearly shown in Fig. 2. At the same time the complementary formations at the opposite end of brace 16 and the upper end of the opposite post, move into engagement as shown in Fig. 2, the

end of the tenon 45 riding over the locking spring 50, the parts being locked in final engaging position as will be obvious. When this occurs, it will be seen that all the joints 5 are locked rigidly in engaging position in which it will be impossible to disengage them except by operations the reverse of those just described.

To complete the superstructure after the 10 post and cross braces have been assembled, the slats 18 are slid into position in the channels 19 with the downwardly extended flanges of the Z-bars 20 extending over the 15 upper edges of the adjacent slats holding same securely in position. The top slats 21 are similarly placed in their respective channels 22, the flanges of the Z-bars 23 engaging adjacent edges thereof. The locking devices 24 on the upper wall slats are 20 engaged in slots 25 of the top slats, thus locking all the slats in position so as not to be removable from the outside. When the doors are hung in position the structure is completed and ready for use. The braces 25 17 extending between adjacent cross braces 16 assist in rigidifying the structure.

In the modification shown in Fig. 10 the post 15' is pivoted with lateral blocks or braces 60 secured thereto near the base 30 thereof said braces having bottom shoulders adapted to engage the upper surface of the base structure when in position to support and brace the same against lateral stresses.

As shown in Figs. 11 and 12 the post 15^a 35 may be braced against movement in one direction by a supplemental brace member 61, disposed closely adjacent to the post, and having a tenon 62 similar to the post tenon 28^a but faced in the opposite direction therefrom. The supplemental bracing member is adapted to be received in a complementary mortise in the base section 1 disposed contiguous to the mortise for the post 15^a. The 40 two mortises are disposed side by side but facing in opposite direction 3 to receive the post and brace respectively.

The post 15^a is engaged with the base 50 structure by entering the tenon 28^a and swinging from a dotted to a full line position as indicated in Fig. 11 in a manner similar to that described above. The brace member 61 is similarly engaged with its mortise by movement thereof from dotted line to full line positions as shown in Fig. 55 11 until its shank 61' aligns with the post. A pin 63 is then slid into the aligning openings 64 in the post and brace respectively, locking the two firmly together. The toes 30^a and 65 of the post and brace respectively 60 engage the extremities of the mortises and function to brace the post in opposite directions, locking the latter firmly in position in the base structure. It will thus be seen that the post is rigidly braced in upright 65 position in the base structure without em-

ployment of additional transverse bracing means, such as the brace 16 described above. It will therefore be obvious that this type of joint is well adapted for rigidly securing one or more posts, or similar structures, in position independently of other posts.

In the modified form of the invention shown in Figs. 13 and 14 the posts corresponding to posts 15 of Figs. 1 to 7 are of metallic channels 70 having webs 71 and inwardly directed flanges 72. The cross braces between the upper ends of these posts is formed of a metallic channel member 73 having downwardly directed flanges 74 and a horizontal web 75. The complementary joint members for connecting the posts are formed of cast metal blocks 76 and 76^a secured between the flanges of the posts, and blocks 77 and 77^a secured between the depending flanges at the opposite ends of the brace. It will be noted that the web 75 overlies the joint at the left in Fig. 13 providing an effective protection against moisture, dirt, etc. It will be understood that tenons are formed at the lower ends 90 of the channel posts similar to tenons 29 on posts 15, and for this purpose, castings similar to castings 76 and 76^a may be secured between the flanges at the lower ends of the posts. Inasmuch as the joint formations at the lower ends of the posts are similar to those shown in Fig. 2 further description of them is considered unnecessary.

The joint shown at the left in Fig. 13 is similar to that shown at the right in Fig. 2, and corresponding parts are correspondingly numbered with the addition of the exponent "a." The joint at the right, however, is modified somewhat from that shown at the left in Fig. 2 for adapting it for 105 metallic construction. As will be seen from the drawing, the casting 76^a projects a short distance beyond the end of post 70 being formed on the inner face with a mortise or recess 78 for receiving the tenon 79 on the casting 77^a. This recess is provided adjacent its lateral walls with depending walls or extensions 80 for receiving the tenon as the brace is swung upwardly into position. These walls not only provide additional 110 support for the tenon but act as guides therefor as it moves home, and provide supports for a locking pin 81 passing through openings therein and engaging the lower side of the tenon. It will also be noted that the tenon 29 is disposed on the brace member and the mortise 28 on the post, as distinguished from the reversed arrangement of corresponding parts as shown in Fig. 5. In other respects the joints shown in modification of Figs. 13 and 14 are similar to those described above in connection with Figs. 1 to 7.

The method of assembly is similar to that described above in connection with Figs. 1 130

to 7 and need not be repeated here in detail. It will be noted, however, that the tenon 37^a on brace 73 is inserted in its mortise while the brace inclines downwardly at its 5 opposite end, the latter then being swung upwardly on said tenon as a pivot until tenon 79 enters between the depending walls 80 of the joint block 76^a, being then moved home into its complementary mortise. The 10 pin 81 is inserted below the tenon holding the parts firmly in assembled position.

As many changes could be made in the above construction and many apparently widely different embodiments of this invention 15 could be made without departing from the scope thereof, it is intended that all matter contained in the above description or shown in the accompanying drawings shall be interpreted as illustrative and not in a 20 limiting sense.

It is also to be understood that the language used in the following claims is intended to cover all of the generic and specific features of the invention herein described, 25 and all statements of the scope of the invention which, as a matter of language, might be said to fall therebetween.

Having described my invention, what I 30 claim as new and desire to secure by Letters Patent is:

1. In a collapsible structure, in combination, a base unit, a superstructure having posts adapted to be detachably secured to said base unit, a brace adapted to detachably engage adjacent posts, and slats detachably engaging said posts.

2. In a collapsible structure, in combination, a base unit, a superstructure having posts adapted to be detachably secured to said base unit, a brace adapted to detachably engage adjacent posts, slats detachably engaging said posts, and means accessible only from the interior for locking the slats in position.

3. In a collapsible structure, in combination, a base unit, a superstructure having posts adapted to be detachably secured to said base unit, a brace adapted to detachably engage adjacent posts, means in said base 50 unit for storing the elements of said superstructure when collapsed, forming a compact self-contained unit of relatively small volume and portable in character.

4. In a collapsible structure, in combination, a base unit, a superstructure having posts adapted to be detachably secured to said base unit, a brace adapted to detachably engage adjacent posts, said base unit having a compartment for storing the elements of said superstructure when collapsed, forming a compact self-contained unit of relatively small volume and portable in character, closure means for said compartment, and means for locking said closure 60 means in closed position.

5. In a collapsible structure, in combination, a base unit, a superstructure including structural members detachably co-operating with each other and with said base unit to form a housing of relatively large dimensions, said base unit being provided with a compartment for receiving said structural members, and closure means for said compartment, whereby said superstructure may be packed into said base unit to form a compact self-contained unit of relatively small dimensions and portable in character.

6. In a collapsible structure, in combination, a base structure, a superstructure therefor comprising frame members movable into locking engagement with said structure and readily assembled or disassembled without use of special tools, and a compartment in said base for receiving the frame members of said superstructure.

7. In a collapsible structure, in combination, a base structure, a superstructure therefor comprising frame members movable into locking engagement with said structure and readily assembled or disassembled without use of special tools, a compartment in said base for receiving the frame members of said superstructure, and means on said base structure for securing said members in said compartment forming a compact unit of relatively small dimensions and portable in character.

8. In a collapsible structure, in combination, opposed posts having joint formations thereon, a brace adapted to extend between said posts and having terminal joint formations complementary respectively with the joint formations on said posts whereby said brace may be moved into locking engagement with both of said posts by a single swinging movement thereof.

9. In a collapsible structure, in combination, opposed posts having means at the lower ends for detachably securing them to the base structure, one of said posts having a mortise with a downwardly extending pocket, a cross brace extending between said posts having a tenon at one end for extending into said mortise and pocket, and means for automatically locking the opposite end of said brace to the other of said opposed posts when said tenon is moved into engagement into said pocket.

10. In a collapsible structure, in combination, opposed posts, one of said posts having a joint formation with a downwardly extending pocket, a wall overlying said pocket, the other of said posts having a joint formation with a downwardly extending lug, a cross brace having a joint formation with a downwardly extending toe for engagement in the pocket of said first mentioned post, said cross brace having a joint formation at its opposite end with a downwardly extending pocket for receiving the

- projection on said second post, whereby said cross brace is movable into locking engagement with both of said posts by single swinging movement thereof.
11. In a collapsible structure, in combination, opposed posts, a transverse brace extending between said posts, and complementary joint formations at the opposite ends of said brace and on said posts whereby said brace is movable into positively locking engagement with said posts by a single swinging movement thereof.
12. In a collapsible structure, in combination, opposed posts, a transverse brace extending between said posts, complementary joint formations at the opposite ends of said brace and on said posts whereby said brace is movable into positively locking engagement with said posts by single swinging movement thereof, and a base element for receiving said posts, said base element and the lower ends of said posts having complementary formations whereby they may be positively engaged by a relative swinging movement thereof.
13. In a collapsible structure, in combination, opposed posts, a transverse brace extending between said posts, complementary joint formations at the opposite ends of said brace and on said posts whereby said brace is movable into positively locking engagement with said posts by a single swinging movement thereof, slats for said structure, and means on said posts and brace for detachably supporting said slats.
14. In a collapsible structure, in combination, opposed posts, a transverse brace extending between said posts, complementary joint formations at the opposite ends of said brace and on said posts whereby said brace is movable into positively locking engagement with said posts by a single swinging movement thereof, slats for said structure, means on said posts and brace for detachably supporting said slats, and locking means accessible only from within for holding said slats in position.
15. In a collapsible structure, in combination, opposed posts, a transverse brace extending between said posts, complementary joint formations at the opposite ends of said brace and on said posts whereby said brace is movable into positively locking engagement with said posts, by a single swinging movement thereof, a base element for receiving said posts, said base and the lower ends of said posts having complementary formations whereby they may be positively engaged by a relatively swinging movement thereof, and a supplemental brace member for one of said posts adapted to positively engage said base member by swinging movement thereof in a direction opposite to the swinging engaging movement of said post.
16. In a collapsible structure, in combination, opposed posts, a transverse brace extending between said posts, complementary joint formations at the opposite ends of said brace and on said posts whereby said brace is movable into positively locking engagement with said posts, by a single swinging movement thereof, a base element for receiving said posts, said base and the lower ends of said posts having complementary joint formations whereby they may be positively engaged by a relatively swinging movement thereof.
17. In a collapsible structure, in combination, opposed posts, a transverse brace extending between said posts, complementary joint formations at the opposite ends of said brace and on said posts whereby said brace is movable into positively locking engagement with said posts by a swinging movement thereof, a base element for receiving said posts, said base and the lower ends of said posts having complementary formations whereby they may be positively engaged by a relatively swinging movement thereof, and a supplemental brace member for one of said posts adapted to positively engage said base member by swinging movement thereof in a direction opposite to the swinging engaging movement of said post.
18. In combination, a post, a base structure for said post, means for positively engaging said post with said structure by relative swinging movement, a brace for said post engageable with said structure by swinging movement opposed to the swinging engaging movement of said post, and means for securing said brace to said post.
19. In combination, a post, a base structure for said post, means for positively engaging said post with said structure by relative swinging movement, and a brace for said post engageable with said structure by swinging movement opposed to the engaging swinging movement of said post, means for securing said brace to said post, said post and said brace being provided with oppositely facing toes adapted for engaging the base structure for bracing said post in different directions.
20. A collapsible receptacle including a base, means providing side walls and a top secured to said base, and means forming a part of one of said receptacle portions and providing a storage compartment for the reception of the other portions when the receptacle is in collapsed condition.
21. A receptacle including a base, means attached to said base and providing the side walls and top for said receptacle, and means forming a part of one of said portions and providing a subsidiary receptacle associated with the receptacle proper.
22. A crate including a base, means providing side walls and a top for said base, said parts being normally interlocked with

each other, and normally inaccessible means for permitting of certain of said parts being disengaged from others of the same.

23. A collapsible crate including a base, 5 side walls and a top portion, said parts being adapted to interlockingly engage with each other, and means within the body of the crate and cooperating with one of the portions aforementioned whereby said part 10 may be separated from the parts which it normally engages.

24. A crate including a base, side walls and a lid portion, said parts being normally interlockingly engaged with each other, and 15 means associated with one of said side walls and cooperating with said lid to normally retain the same in position, said means being capable of being manipulated to permit the removal of said lid portion from the 20 side walls which it engages.

25. A crate including a base formed with a pair of recesses disposed adjacent to and diverging with respect to each other, side walls for said crate, a lid attached to said 25 side walls, posts forming a part of said side walls, a tenon forming a part of one of said posts and adapted to extend into one of said recesses, a second tenon forming a part of another post and extending into the second

of said recesses, said latter posts being disposed adjacent to each other and means co-operating with said posts for normally preventing movement of one with respect to the second of the same.

26. A crate including a base, side walls 35 and a lid portion, posts forming a part of said side walls, curved tenons associated with certain of said parts, others of said parts being formed with complementary recesses, said tenons normally extending into said recesses. 40

27. A crate including a base, side walls and lid portion, channel members forming a part of said side walls, blocks positioned adjacent to one of the ends of certain of said channel members, an extended portion 45 forming a part of each of said blocks and projecting beyond the end of the channel member with which it is associated, the next adjacent part of said crate being formed with the recess corresponding in configuration to the shape of said extended portion.

In testimony whereof I affix my signature, in the presence of two witnesses.

JOHN J. SHEA, JR.
